(57) **CLAIM**

The ornamental design for a base for water distiller, as shown.

DESCRIPTION

FIG. 1 is a perspective view of the design;
FIG. 2 is a left side elevational view of the design;
FIG. 3 is a front elevational view of the design;
FIG. 4 is a right side elevational view of the design;
FIG. 5 is a rear elevational view of the design;
FIG. 6 is a top plan view of the design; and,
FIG. 7 is a bottom plan view of the design.
